UNITED STATES PATENT OFFICE.

ALFRED H. DAEHLER, OF LOS ANGELES, CALIFORNIA.

METHOD OF AND APPARATUS FOR CONVEYING AND MIXING CONCRETE.

1,201,155.

Specification of Letters Patent. Patented Oct. 10, 1916.

Application filed February 24, 1909. Serial No. 479,852.

To all whom it may concern:

Be it known that I, ALFRED H. DAEHLER, citizen of the United States, residing at Los Angeles, in the county of Los Angeles and State of California, have invented certain new and useful Improvements in Methods of and Apparatus for Conveying and Mixing Concrete, of which the following is a specification.

10 This invention relates to a method of and apparatus for delivering a mass of liquids and solids to suitable places of use or deposit, as in the construction of buildings and the like.

15 One of the principal objects of this invention is to supplant the present methods of transportation of plastic building material from the mixer to the molds by a systematic method embodied in a single compact and portable device in which a stream or jet of semi-fluid material under pressure is caused to discharge into suitable troughs or other receptacles and in which the stream or jets are constantly under the control of 25 the operator.

The conveyance of concrete and semi-fluid building material to its destination is coupled with an extraordinary absorption of time and labor, and above all, considerable waste; the concrete when delivered is not in the same condition as it was when discharged from the mixer since the more composite and heavier particles of the concrete mixture are found to have settled, while the 35 water has nearly separated itself from the body, thus leaving the concrete in an unfit condition and causing the same to crack and chip by reason of the incomplete mixing of the two necessary ingredients.

40 It is therefore a further object of this invention to provide a method of and apparatus for delivering a semi-fluid building material in a thoroughly mixed condition, and if desired in a more complete mixed condition than when it was discharged from the mixer, and to so deliver the material that, during its course of travel to its place of deposit, the component ingredients will not become separated.

50 While this invention contemplates the employment of preferably pneumatic pressure though any other pressure means may be employed upon a confined body of building material in a state of semi-fluidity to cause

a stream to be projected through nozzles or pipes, it is not to be confounded with devices for the delivery of granular, amyloaceous or pulverulent material, in which the pneumatic means is used principally, in fact solely as a blast, because the essential object of this invention would be defeated by a blast.

With the above and other objects in view, the invention consists of the new and useful method of conveying fluids or semi-fluids and solids, and in the provision of simple means for effectively carrying out the method, a preferred embodiment of such means appearing in the accompanying drawings, and the invention being particularly pointed out in the claims.

In the drawings, Figure 1 is a front elevation of apparatus constructed and organized in accordance with the invention, parts being omitted and parts being broken away to illustrate interior construction. Fig. 2 is a bottom plan view taken on the line $x^2 x^2$, Fig. 1 showing the construction and arrangement of valves. Fig. 3 is a fragmentary sectional detail view illustrating valve construction, and showing the provision of a flexible and elastic washer. Fig. 4 is an enlarged end elevation showing in detail the treadle mechanism for governing the float and the operating mechanism for the lower valve. Fig. 5 is a side elevation of a pipe adapted to connect the outlet from a pressure chamber with a stand-pipe having a helical conveyer disposed therein and adapted to be substituted for the standpipe shown in Fig. 1. Fig. 6 is an enlarged fragmentary vertical sectional view showing a helical conveyer in the standpipe forming a portion of the apparatus. Fig. 7 is an enlarged fragmentary sectional elevation showing a swivel joint employed in connection with the helical conveyer. Fig. 8 is a side elevation showing a derrick and pipe suspended therefrom, mechanism for adjusting the pipe and complementary mechanism for governing the discharge end of the concrete conveying pipe. Fig. 9 is a fragmentary sectional illustration of a double swivel. Fig. 10 is a plan view showing the derrick and concrete conveying pipe, the operator's platform and the mechanism for controlling the valve in the discharge end of the pipe. The material is shown discharging into a mold.

Fig. 11 is a fragmentary sectional view on the line $x^{11}-x^{11}$ Fig. 8, showing the operator's platform and the valve for controlling the flow of concrete from the discharge end 5 of the pipe.

In carrying out my invention I have illustrated an apparatus, which, though complete in all mechanical details and capable of executing the objects recited in the pre- 10 amble, is susceptible of infinite changes, structurally and mechanically, the present illustration being the preferred embodiment of the invention.

The apparatus consists of two inclosures 15 or tanks A and B mounted on a suitable removable base 1, and having bolted or otherwise removably secured to the top thereof a hopper 2, whose outlet communicates with a pipe 3 having two branches 4 and 5. The outlets from said branch pipes 4 and 5 are respectively controlled by valves 6 whose stems 7 extend upward through bosses 8 provided respectively, on the said branches 4 and 5. On the ends of the stems 20 25 of the valves are secured cranks or operating levers 9, by means of which the discharge of material from the hopper into the respective tanks A and B is either permitted or cut off according to necessity. These 30 valves 6 consist of substantially segmental members having a sharp cutting or shearing edge 10 Fig. 2 whereby the flow of material is quickly cut off from the supply.

The bottom of the tank A is provided with 35 a boss 11, onto which is bolted an outlet pipe 12. Operating transversely within said pipe 12 is a valve 13. The stem 14 of said valve 13 extends through a boss 15 provided, on the pipe 12 and the end of said stem has its 40 bearing in a boss 16 mounted on the base 1.

A crank 17 is fastened to the valve stem 45 14 of the valve and is connected by swivel means at 18 to a valve controlling lever 19 having a bifurcated extremity 20 which straddles a lug 21 fixed on the base 1, and onto which lug said bifurcated end is pivoted by pin or bolt 22. The said pipe 12 communicates with a pipe 23 which is secured to the bottom of the tank B. The tank 50 B is likewise provided with a boss 11 onto which the pipe 23, is secured. Operating transversely within said pipe 23, is a valve, not shown, but similar to the valve 13, operating in pipe 12. The stem 14, of such 55 valve, extends through a boss 15 on the pipe 23, which boss is similar to the boss on pipe 12. The parts described in connection with tank A, to-wit: boss 16, crank 17, swivel means 18, controlling lever 19, lug 21, and 60 bolt 22, are duplicated on tank B.

The tanks A and B are each provided with indicating mechanism and controlling means therefor, connected to the respective levers 19, associated with the tanks, and organized in substantial duplication, wherefore the

following description of the mechanism on the one tank will answer for the description on the other.

Extending away from one of the furcations of the forked extremity of the lever 19 70 is an arm 24 provided with a slot for the accommodation of one end of a rod 25. A nut 26 is provided on said rod 25 and acts as an abutment for the arm 24. The other end of said rod 25 is operatively connected 75 to a treadle 27 through its support which extends through a hollow boss 28 provided on the tank, and which terminates in a rod 29 carrying at its extremity a float 30.

The rod 25 is provided for the purpose of 80 preventing the valve 13 from closing on or striking the float 30, since, when the float has descended into the outlet from the tank for purposes to be presently made clear, the operation of the lever 19 to control the 85 valve to cut off the flow from the tank will simultaneously control the rod 25 and consequently the float 30 so that the float will have risen to a distance sufficient to prevent the valve from closing upon the float. 90

Onto the support of treadle 27 is pivotally secured a stem 31 linked to the end of an index 32 pivoted on the tank.

In Fig. 4 the treadle mechanism is fully shown. The treadle 27 is pivoted on the 95 end of a rod 33 and is provided with a lug 34 onto which one end of a connection 35 is pivoted while the other end of said connection is pivoted to a pawl 36 mounted on the rod 33, which pawl is normally under 100 the tension of a spring 37 whereby the pawl is disengaged from the shoulder 38 provided on the hollow boss 28 when the float has reached its highest position within the tank, which position is determined by 105 the level of the material, which, rising higher than the float, as set by the operator, carries the float with it and automatically unlatches the pawl from the shoulder and allows the float to descend with the material. 110 When the valve is opened to allow the material to discharge from the tank the float 30 follows the level of the material in the tank until the lowest position is reached which is indicated by the index 32. The operation of 115 the treadle raises the float to its normal position again.

The material in the tanks A and B is under pneumatic pressure supplied to the top of the tanks through pipes 39 and 40, 120 respectively, connected with supply pipe 41 and controllable by valves 42 and 43, respectively, 44 is an exhaust pipe for the air. 45 is a pipe for the conveyance of the material, the said pipe being connected with 125 the pipe 23 by a joint or elbow 46 provided with a flange 47 whereby to removably fasten it to the base 1.

In order to assist in the elevation of the material to considerable heights and to 130

further insure the thorough mixing of the concrete in its ascent where the consistency of the material makes the elevation more difficult, I provide in the pipe 48 (shown in Fig. 6) a helical conveyer 49 fixed upon a revoluble shaft which is given motion by bevel gears 50 and a pulley 51. The said pipe 48 is mounted on a base 52 and is designed to be connected with the supply pipe 23 by the pipe 53 shown in Fig. 5. By the provision of a mechanical means in the pipe, and the employment of pressure on the mass, both solid and liquid portions of the mass are conveyed simultaneously.

15 In Fig. 3 I have illustrated a method of insuring the retention of the air in a tank after its valve 6 has been operated to cut off the supply of concrete to the tank, where the valve does not seat itself. This method 20 consists in the provision of a flexible and elastic disk or washer 54 fastened to the bottom of the valve and extending beyond the periphery of the same, so that the air pressure within the tank will cause the 25 flexible projecting periphery of the strip to be forced against the pipe and valve and thereby prevent the escape of any air. In connection with said pipe 48 in which a helical conveyer is employed to assist in the 30 elevation and intimate mixing of the concrete, a cap 55 having a flange 56 is provided, which cap is arranged to sit upon the pipe 48 and to be revolvably secured thereon by a rabbeted collar 57 bolted upon the 35 flange 58 of the pipe 48. This cap serves the twofold purpose of forming a bearing for the shaft 59 of the spiral conveyer 49 and a joint for sections of pipe to be used, so that the delivery outlet from the supply pipe 40 may be moved in all directions without impeding the flow of material therethrough, thereby rendering it capable of discharging into places of deposit wherever located, consistent with the dimensions of the apparatus.

45 To facilitate the deposit of concrete into the molds either on level or elevated planes, a derrick may be used. This derrick consists of a base 60 mounted to rotate in a suitable housing 61. Pivoted upon said base 60 50 is a truss or boom 62 adapted to be raised and lowered by a cable 63 extending over a roller 64 provided in the brace 65 which is spaced for the accommodation of the truss or boom 62. Any means for winding or 55 unwinding the cable 63 may be employed, such, for instance, as a train of gears shown at 66.

Extending upwardly through the base 60 of the derrick is a pipe 67, which is a continuation of the aforementioned pipe 45 and on which is swiveled a cap 68. In said cap 68 is also swiveled another pipe 69. By this means the pipes may be rotated in all directions, either with or independently of 65 the revolution of the derrick and its com-

plementary parts. The end of the pipe 69 is also provided with a swivel arrangement to receive another pipe 70, and this arrangement may be carried out indefinitely. The jointed pipes 69 and 70 are suspended from 70 said truss or boom by tackles 71 operating over the pulleys 72.

To control the movement of the pipe 69 a windlass is provided on the pipe 70 which is operated by a hand wheel 73, while to 75 control the movement of the discharging pipe 70, a windlass 75 mounted on the pipe 70 is employed, in this manner to govern the various necessary movements of the pipes either simultaneously or independently of each other.

78 designates a gate valve for cutting off or permitting the discharge of material from the pipe.

79 designates a platform pivotally suspended from a strap 80 encircling the pipe 70, said platform being secured against any swinging motion and maintained in a horizontal plane by the rod 81 pivoted at one end to a cross rod 82 provided on the platform, and the other end of which is fastened to a pivoted link 83 attached to the joint between the pipes 69 and 70. Another rod 84 is likewise pivotally secured to said link 83 and to the cap 68. In this manner the 95 platform 79 is steadily held in a horizontal position.

Suitable means for moving the derrick and discharging pipe as well as the platform may be employed, such, for instance, 100 as a rope or cable 85.

86 represents a counterbalancing receptacle mounted on the base 60 of the derrick. If desired, the entire tank arrangement, with its component parts, may be provided with 105 wheels to render it portable.

The operation, method of use and advantages of the apparatus and method will be readily understood from the foregoing description taken in connection with the accompanying drawings and the following statement:—In the form of apparatus illustrated, the material to be conveyed is admitted to the tanks A and B, alternately, 110 from the hopper, by opening the respective valve 6, the respective discharge valve 13 being closed during such admission. When a tank has received its charge of material, its valve 6 is closed, the pressure means for the 115 respective tank is permitted to act to expel the material from the tank and force it into the pipe line connected therewith, the respective discharge valve 13 being opened when the tank is filled and after the inlet valve 6 has been closed, and at the time the 120 material is to be expelled from the tank. After the material in a tank has been expelled by maintaining pressure thereon, the respective discharge valve 13 is closed, the 125 pressure may be relieved, and the respective 130

inlet valve 6 may be opened to recharge the tank. By alternately filling and discharging the tanks, and controlling the rate of discharge through the pressure controlling means, shown as the valves 43 and 44, material under pressure may be continuously transferred to the pipe line. The pressure in a tank may be supplied or released, as required, by manipulation of the 5 respective air valve of the pressure controlling means. Concurrent with the application of pressure on the material deposited alternately in the tanks, the screw 49, in the pipe 48, connecting with the tanks, is set in motion by its operating means, as by power applied to the pulley 51, whereby the fluid or semi-fluid ingredient is elevated or conveyed simultaneously with the solid portion. In this manner and by the means referred to, 10 the mass may be continuously delivered to its places of deposit, with the proper proportions maintained of the solids and fluids or semi-fluids.

What I claim is:

25 1. The combination with a plurality of concrete or other building material receiving tanks, having inlets and outlets, of valves to control said inlets and outlets, a vertical delivery pipe connected with the outlets from said tanks, means to supply fluid pressure to the top of the material in said tanks to force the material upwardly through said pipe, and an elevator in said delivery pipe to assist in the elevation of the material 30 therethrough.

2. The combination with a plurality of concrete or other building material receiving tanks, having inlets and outlets, of valves to control said inlets and outlets, a delivery 35 pipe connected with the outlets from said tanks, means to supply fluid pressure to the top of the material in said tanks to force said material through said delivery pipe, and a screw lift in said delivery pipe to assist in the elevation of the material therethrough, said screw lift also serving to keep the material in agitation.

3. The combination with a plurality of concrete or other building material receiving 40 tanks, having valve controlled inlets and outlets, of a delivery pipe connected with the outlets from said tanks, means to supply air under pressure to the top of the material in said tanks to force the material through 45 said delivery pipe, a screw lift in said delivery pipe to assist in the elevation of the material therethrough and to keep the material mixed, means to revolve said screw lift, and means to indicate the level of said 50 material in said tanks.

4. The combination with a plurality of concrete receiving tanks having inlets and outlets, of valves to control said inlets and outlets, a pipe connected with the outlets 55 from said tanks, means to supply pressure

to said tanks to force material through said pipe, a screw lift revoluble in said pipe, a flexible delivery pipe universally joined to said first-named pipe, a suspending means for said delivery pipe, a means carried by 70 said delivery pipe to universally swing said delivery pipe, and means to control the discharge of material from the discharge end of said delivery pipe.

5. The combination with concrete or other 75 building material receiving pressure chambers, and means for supplying pressure thereto, of a pipe connected with the outlets from said pressure chambers, a revoluble screw lift in said pipe, a sectional universally jointed pipe line connected with said first named pipe, means for revolably suspending said pipe line, means carried by the discharge end of said pipe line to adjust same vertically, horizontally and laterally, 80 and means for controlling the outlet from the discharge end of said pipe.

6. The combination with concrete or other building material receiving tanks, and means to supply pressure to said tanks, of a pipe 90 connected to the outlets from said tanks, a flexible jointed pipe connected to the first named pipe, means for suspending said pipe, means to universally adjust said pipe, means to control said means, a mechanical means to 95 agitate and assist in conveying material through said pipe and means for operating said mechanical means.

7. In a machine for delivering a mass of liquids and solids to suitable places of deposit, the combination with a pipe line, of mechanical means in said pipe line to convey the solids therethrough, an operating means for said mechanical means, means to maintain pressure on the mass to convey the 100 liquid portion thereof through said pipe line simultaneously with the conveyance of said solids, and means to control said pressure means.

8. In a concrete machine, a concrete or 105 other building material receiving receptacle, a pipe line connected with said receptacle, mechanical means in said pipe for elevating the larger concrete aggregates, a pressure means cooperating with said mechanical 110 means to elevate the liquid portions in said pipe line and simultaneously with the elevation of said larger concrete aggregates, means to operate said mechanical means, and means to control said pressure means.

9. The method of mixing and conveying the ingredients of concrete that consists in mechanically propelling and mixing the solid ingredients thereof and simultaneously subjecting the liquid ingredient and the 115 solid contained in said liquid ingredient to conveying and mixing fluid pressure while said liquid and contained solids are being mixed and conveyed with said solid ingredients.
